NEWSPAPER VENDING MACHINE

Daniel D. Cameron, San Francisco, Calif.

Application May 27, 1943, Serial No. 488,680

5 Claims. (Cl. 312—57)

The invention relates to a machine for vending newspapers, magazines, and the like, and particularly to vending machines of this type which are coin-controlled.

An object of the invention is to provide a vending machine of the character described in which the mechanism for withdrawing and delivering the papers from the machine will be positive and certain in operation, will insure the delivery of a paper each time the machine is operated, and yet will operate in such a smooth and easy manner as to require almost no effort for actuation, and entail practically no appreciable wear.

Another object of the invention is to provide a machine of the character described in which the means of controlling the release of the papers one at a time, and the means of delivering each of the papers through the machine for discharge, is provided for by a single moving part.

A further object is to provide a means of the character described in which the papers will be supported in such manner that the delivery operation will be considerably facilitated by the weight of the paper to be delivered and the lack of friction between the papers and between the paper to be delivered and the support therefor.

A still further object of the invention is to provide a very simple but effective means for readily adjusting the machine to enable it to handle papers of different thicknesses, such as daily and Sunday editions, and varying daily editions.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a vertical sectional view of a vending machine made in accordance with my invention.

Figure 2 is a fragmentary sectional view similar to Figure 1, but with some of the parts in a different operative position.

Figure 3 is a fragmentary view similar to Figure 1, but showing the machine adjusted for a different thickness of newspaper.

Figure 4 is a horizontal sectional view of a portion of the machine taken on the line 4—4 of Figure 1.

Figure 5 is a detail vertical sectional view of

the adjusting means of the device shown in Figure 1 and taken at right angles thereto.

The machine of my invention as illustrated in the drawing, comprises a casing 5 having front and rear walls 7 and 8, and walls 9, and top and bottom walls 12 and 13, such casing serving to contain the papers to be vended and the mechanism for effecting the delivery thereof. Extending between the rear and front walls of the casing is a plate 14 which serves to partition the casing into two compartments 16 and 17 and to form a support for the papers 18 in the machine. The compartment 17 which is below the plate 14 is designed to contain the mechanism aforesaid, while the compartment 16 which is above the plate and whose bottom is defined by plate 14 is arranged to contain the papers.

The wall or cover 12 is preferably connected to the rear wall 8 by means of a hinge 19 in order to permit the papers to be inserted in the compartment from the top, and such cover may be locked in closed position by suitable means. As will be clear from Figure 1, the papers are arranged to be held in the compartment in side by side relation in substantially vertical position and parallel to the front wall 7, and with the folded edge of the papers lowermost and normally resting upon plate 14. In the front wall 7 is formed an opening 21 which is covered by a glass or other transparent plate and thus exposes to view from the exterior of the casing the headlines on the papers.

By means of a follower plate 22 which is connected to the end walls 9 by links 23 and arranged to engage the rearmost paper, the papers in compartment 16 are urged forwardly so that they may be caused in the manner to be herein-after explained, to be discharged to a delivery opening 24 adjacent the forward edge of plate 14. Preferably by inclining the plate 22, the papers are caused to assume a slightly tilted position, that is with the lower portion extending forwardly, and in such manner that the forward positioning of the papers can be normally arrested entirely by contact of the lower portion of the foremost paper with some abutment adjacent the forward edge of plate 14 but inwardly of the delivery or discharge opening 24. This arrangement for the advance and retention of the papers it will be noted avoids the need of a full height stop or retaining member for the foremost paper and thus eliminates the resultant friction between the paper and such member when the paper is raised or lowered as a part of the releasing and discharging operation. For facilitating the ad-

vance of the papers over the plate 14, the latter is desirably declined toward the discharge edge.

As above set forth, means are provided to serve as a stop for the foremost paper so that until the machine is appropriately operated, neither such paper nor the papers to the rear may be moved into the discharge opening 24. As here shown such means is in the form of a yoke member 26 which is positioned at the forward edge of plate 14 and has provided at the side adjacent the papers a sloping shoulder 27 against which the foremost paper is arranged to abut. Preferably the top of the member 26 extends toward the discharge opening 24 and is provided with an apron 28 which defines a part of said opening.

As an important part of my invention, a very simple but effective means is provided which is operative under appropriate conditions, for raising the foremost paper, that is the one in contact with the shoulder 27, so that the lower edge of the paper will clear the shoulder, and then move such edge portion over the member and release it whereby the paper by its own weight may descend out through the delivery opening. Arranged in the casing immediately forward of and parallel to the forward edge of plate 14 is a shaft 31 which is suitably mounted for rotation in bearings in the end walls of the casing, and has fixed thereon for rotation therewith a plurality of arms 32 which are arranged to move through notches 33 in the plate and member 26 and into the path of the lower edge portion of the paper which may be in contact with shoulder 27. The side of the arms designed to move under and engage the paper is preferably recessed in order to adequately engage and hold the paper on the arm, and as will be clear from the drawings, the free end of each arm is so related to the positioning of the papers, that since it moves between the foremost paper and the one immediately to the rear, only the foremost paper will be operatively engaged and elevated by the arms. By reference to the drawing it will be seen that when the recessed side of the arms is positioned as in Figure 1 under the paper and the shaft then rotated, the paper will be raised from the plate 14 and the bottom portion carried completely over the member 26 as shown in Figure 2, in which position the paper will have moved out of the arm recesses and caused by gravity to descend through the delivery opening.

Rotation of the shaft 31 is arranged to be effected by a crank 34 secured to an end of the shaft extending from the casing. Operation of the shaft is coin-controlled, and suitable mechanism therefor may be inserted in a compartment 36 and operatively connected to the shaft in a well known manner. In the present form of the invention, the machine is arranged to be operated to deliver a paper by moving the shaft in one direction and then moving it back in the reverse direction for positioning the arms for a subsequent delivery operation. A spring 38 fixed to an arm 38 on the shaft serves as a means of returning the shaft and crank to the starting position indicated in Figure 1, and in order to limit the oscillating movement of the shaft to the initial and final positions illustrated in Figures 1 and 2, pins 35 are fixed to the casing and arranged to engage the arm 38. In view of such oscillating movement of the shaft, and the need for preventing the succeeding paper from moving forwardly and into engagement with member 26 while the arms are operating on the foremost paper and before the arms have returned

to starting position, such arms are preferably formed with arcuate portions 39 back of the recessed faces, which are arranged to engage said succeeding paper and keep it from advancing during the forward movement of the arms and the return movement until the starting position is attained. Preferably the free end of the arms is provided with needle points 40 which insure a positive grip with the paper as the arms elevate and move the paper over the member 26.

As a means of adapting the machine for handling papers of different thicknesses without the necessity of replacing parts or making relatively extensive adjustments, I provide for the adjustable positioning of the member 26. As will be seen from Figure 1, such member is carried at each end by a lever 41 one of which is provided at each end of the casing and fulcrumed thereto as at 42. The member has a pivotal connection 43 with the levers and is loosely held by means of one or more tongues 44 engaging in corresponding transverse slots in the base portion 46 of the paper delivery chute. By shifting the position of the lever the position of the member 26 will be accordingly changed with respect to the edge of the plate 14. Thus if the member is moved to a more forward position, a thicker paper may be accommodated as will be clear from Figure 3, while if the member is moved closer to the plate as in Figure 1, a relatively thin paper is accommodated. In each instance the end of the arms will engage the folded portion of the papers. Preferably three positions of adjustment of the member are provided for, such variation being afforded by engagement of a catch 45 on the lever with spaced notches 47 provided on a fixed plate 48. Catch 45 is as here shown in the form of a trigger 50, pivotally fixed to the lever and resiliently held in engagement with one of the notches 47 by means of a spring 51.

If desired, the arms may be used as the abutment means for retaining the advanced or foremost sheet in position. This may be readily done by utilizing the portion 39 of the arm as a shoulder as indicated in Figure 3. Such an arrangement would eliminate the need of the member 26 and would be advantageous where no adjustment for variation in thicknesses of paper is required.

I claim:

1. In a newspaper vending machine, a casing having a downwardly and forwardly extending support, a device to hold the papers in substantially vertical rearwardly tilted position with the bottom of the papers resting on the support, means at the front of said support providing a discharge chute for the paper from the support, rotatably mounted means in the casing interposed between said first means and the support formed to provide a stop portion positioned to engage the foremost paper on the support and arrest the advance thereof, a third means having provided thereon a member arranged to engage the bottom of said paper and operative upon rotation of said latter means to elevate said paper over said stop portion and convey same to said chute, and said rotatable means having provided thereon a portion positioned to move into engagement with the paper immediately to the rear of said foremost paper and arrest the forward movement thereof when said member moves the foremost paper over said detent portion.

2. In a newspaper vending machine, a casing, means in the casing to support the papers in upright position, means urging the advance of the papers over said supporting means, means at the

front of said supporting means defining a discharge opening for papers moved from said support, stop means for the foremost paper, rotatably mounted oscillatable means between said support and discharge opening comprising a shaft, an arm carried thereby and arranged for positioning exclusively under the foremost paper on said support and whereby upon rotation of said shaft in one direction said arm will elevate said paper and move it forwardly toward said discharge station, said arm having a recessed side arranged for engagement with the paper for the elevation thereof, and said arm being formed with an arcuate portion arranged to engage the paper to the rear of the foremost paper when the recessed side is in position elevating the foremost paper and engaging the rear side of the foremost paper and guiding the latter to said opening when said arcuate portion is in position arresting said rear paper, means to limit the amount of oscillation of said rotatable means in opposite directions, said arcuate portion being of such form and extent that the rear paper will be held against advance on said support during the elevating movement of the foremost paper and during and until the rotatable member is repositioned for elevating a paper on the support, and means for oscillating the rotatable means from the exterior of the casing.

3. In a newspaper vending machine, a casing provided with a paper insertion opening and a cover over the opening and at a side thereof having a paper delivery opening and an inclined support formed in the casing for holding the newspapers in upright position and for advance to said delivery opening, an abutment member interposed between the support and delivery opening and positioned to engage the foremost paper on the support and arrest the advance thereof to such opening, movable means mounted for positioning under said paper for engaging the bottom of the paper and elevating same above said abutment member, said abutment member being adjustably mounted to vary the advance positioning of said paper on the support and in relation to said mov-

able means, and means within the casing for moving said abutment member to and holding same in any of a plurality of different positions of adjustment, said last mentioned means including a lever fulcrumed in the casing and one arm pivotally connected to and carrying said abutment member, and the other arm having its free end located adjacent said insertion opening.

4. In a newspaper vending machine, a casing having a paper delivery opening and a support inclined therein formed for holding the newspapers in upright position and for advance to said opening, an abutment member mounted for adjustable positioning between the support and opening and having a shoulder for engagement with the foremost of said papers, and a rotatable member having its axis along said abutment member and mounted to engage the bottom of said foremost paper and raise same over said shoulder.

5. In a newspaper vending machine, a casing having a paper delivery opening and a support sloping downwardly and forwardly toward said opening, means cooperating with said support to hold the papers in upright position thereon and to urge the papers toward said opening, a yoke member at the forward end of said support comprising a shoulder portion projecting upwardly therefrom to engage and arrest advance of the foremost of said papers and having a portion defining a guide for the paper from said shoulder portion and to the delivery opening, a shaft extending through said yoke and mounted to oscillate in the casing, means on said shaft having a part movable through the plane of said shoulder portion to elevate the foremost paper above said shoulder and to said guide portion and having a part arranged to engage the next foremost paper when said first part is in elevated position, means adjustably supporting said yoke member relative to said elevating part and selectively operatable from the interior of the casing exclusively, and means externally of the casing for actuating said shaft.
